PACKING MEANS FOR CIGARS.

1,148,806.

Specification of Letters Patent.

Patented Aug. 3, 1915.

Application filed September 9, 1914. Serial No. 860,940.

To all whom it may concern:

Be it known that I, HORACE G. SLATER, a citizen of the United States, residing at Los Angeles, in the county of Los Angeles, State 5 of California, have invented a new and useful Packing Means for Cigars, of which the following is a specification.

The invention relates to cigars, and the principal object thereof is to provide means 10 for packing cigars in such a manner that an emblem or mark will be impressed thereon and will be retained regardless of when the cigars are used.

As cigars differ widely in quality it is 15 very desirable that they be properly marked to indicate the maker's name and quality, or other trade-mark, and that this marking be so impressed upon them that substitution of inferior goods will be difficult. It is common 20 practice to place upon cigars a paper band and it is common to brand the wrapper of a cigar to indicate their quality or origin. By using my invention I impress or emboss in the cigar any desired trade-mark.

As the material from which cigars are made is of a fibrous nature, particularly susceptible to heat and moisture, it has been extremely difficult in the past to retain impressions made on cigars if they are marked before 25 being packed, especially as they are ordinarily packed in a moist or soft condition and compressed to an appreciable extent when the lid of the box is closed, thereby destroying impressions or marks made on 30 the cigars before packing. By using my invention I not only make an impression on the cigar but I provide means for causing the cigars to retain this impression until 35 they are actually removed from the box and sold.

Referring to the drawings, which are for 40 illustrative purposes only: Figure 1 is a perspective view of a box, a portion of the cigars being removed and the marking means being cut away to better illustrate the invention. Fig. 2 is a section on the plane x^2-x^2 of Fig. 1. Fig. 3 is a perspective view of a portion of the marking means.

In these drawings the cigars 10 and 11 are 45 packed in two rows in a box 12 having a cover 13. A marking strip 14 is inserted between the cigars 10 and 11 and a second marking strip 15 is inserted between the cigar 11 and the cover 13. The cigars 10

and 11 are ordinarily packed in the box 12 55 in a partially moist condition and the marking strips 14 and 15 are preferably of light sheet aluminum having raised letters 16 formed thereon. The strips are placed in the box with the raised side against the 60 cigars and the cover 13 is secured in place, thus forcing the raised letters 16 into the body of the cigar without breaking the wrapper but very effectually marking the 65 same. If this marking is impressed on the cigar before it is placed in the box and no means is provided for retaining it, the natural elasticity of the tobacco as it is affected by atmospheric changes in humidity and 70 temperature together with the pressure exerted by the lid of the box when closed will tend to cause this marking to be gradually obliterated so that eventually the marking 75 will be very faint. By placing the marking means in the box against the cigar and allowing it to remain in this position until the cigar is finally marketed the marking is retained in all its sharpness and the expansion and contraction of the cigars under atmospheric conditions only serves to more perfectly 80 perpetuate the impression.

It is further to be noted that the wrapper of cigars is of delicate texture and for this reason attempts made heretofore to produce a lasting impression have failed as any attempt to place an impression in a cigar in a short space of time is too violent and harmful to the wrapper. In branding also great care must be exercised as the heat of the iron very quickly injures the wrapper thereby 85 spoiling the drawing quality of the cigar 90 when smoked.

With my invention the impression is made as heretofore pointed out when the cigars are in moistened and soft condition continuing over a long period of time and the depth of the impression made is slight compared to that necessary when a cigar is marked at a single operation before packing, as in such case the depth of the impression must be 100 made quite deep allowing if possible for the change in the cigar when packed and in the box.

I claim as my invention:

1. A branding and brand preserving 105 means for cigars consisting of a strip of material having a trade-mark embossed thereon, said strip being of suitable size to

be placed and retained between the layers of cigars in a box, the markings thereon being so located as to properly impress the trade-mark on each cigar.

5 2. A branding and brand preserving means for cigars suitable for placing between the layers of cigars in a cigar box, consisting of a thin sheet of aluminum having an embossed trade-mark so located as to

be impressed on each cigar when pressure is 10 exerted on the various layers.

In testimony whereof, I have hereunto set my hand at Los Angeles, California, this 3rd day of September, 1914.

HORACE G. SLATER.

In presence of—

STATA ARBUTHNOT,

FRANK L. A. GRAHAM.
